UNITED STATES PATENT OFFICE.

PHILIP MUELLER, OF DECATUR, ILLINOIS, ASSIGNOR TO H. MUELLER MANUFACTURING COMPANY, OF DECATUR, ILLINOIS, A CORPORATION OF ILLINOIS.

LAVATORY-FITTING.

942,386.

Specification of Letters Patent. Patented Dec. 7, 1909.

Application filed November 21, 1907. Serial No. 403,243.

To all whom it may concern:

Be it known that I, PHILIP MUELLER, a citizen of the United States, and resident of Decatur, Macon county, State of Illinois, have invented certain new and useful Improvements in Lavatory-Fittings; and my preferred manner of carrying out the invention is set forth in the following full, clear, and exact description, terminating with

10 claims particularly specifying the novelty.

This invention relates to baths and closets, and more especially to bath and basin fittings, and the object of the same is to facilitate the attachment of the fitting to a bath

15 tub and the coupling of a single or compound faucet thereto.

Another object is to facilitate the attachment of the fitting to a basin slab or sink and the coupling of a faucet thereto.

20 To this end the invention consists in the provision of two nuts between which the lavatory member is clamped, one nut being threaded on the supply pipe and the other applied thereto—here shown as carried by

25 and preferably threaded on the exterior of a sleeve which latter is itself threaded on the supply pipe.

The following specification sets forth one embodiment of these ideas, taken in connection with the accompanying drawings forming a part thereof and in which—

30 Figure 1 is a plan view of a compound cock applied to the rear end of a bath tub which is shown in dotted lines, certain parts being illustrated in section. Fig. 2 is a side elevation of a stationary washstand with the slab in section, illustrating the invention as applied thereto and the coupling and base of the faucet slightly removed from the

40 sleeve. Fig. 3 is a central section through parts of this fitting, showing both nuts on the sleeve.

The supply pipe 1 is preferably continuous from its juncture 2 with the service pipe 3 (which juncture may be a wipe joint beneath the flooring or within the wall) to and through the tub wall 4 or basin slab 5. If this pipe rises from the floor it may make a single or compound bend 6 so as to project properly through the end of the tub wall, if it projects out from the building wall it will make the same bend so as to pass upward through the basin slab, but if it projects outward from the building wall 55 toward the tub or straight upward from

the floor toward the slab the bend will be omitted. In any event it is a nickel or tastefully finished pipe, and the joint with the service pipe is concealed from view.

The end of the supply pipe where it 60 passes through the tub wall or slab is threaded exteriorly as at 9 for some distance, and screwed thereon is an outer nut 10 which may have a wrench hold 11 or wings 12, and this nut bears against the outside of the 65 tub or the bottom of the slab. Screwed also on these threads is a sleeve 13 which carries a radial flange 14, mounted thereon in any suitable manner, and applied to the threaded end 9 by said sleeve. In the drawings the sleeve is shown as exteriorly threaded as at 130 from its outer end for a portion of its length, and smooth as at 131 for the remainder of its length excepting at its inner end where it is shaped as described below. The flange 14 is shown as projecting radially from an integral hub 140 which screws onto the sleeve and therefore constitutes a nut. The inner end of this hub or nut is preferably provided with a wrench 75 hold 15 as shown, and the flange may be dished somewhat as at 16 so that the outer end of the hub is formed into an annular extension 17 which may be made long enough to enter the hole 18 in the lavatory member 80 and center the nut therein. The interior of this nut is preferably threaded as at 141 for a portion of its length to engage the threads on the sleeve, and has a smooth bore 85 142 for the remainder of its length or within the wrench hold—this construction permitting the entire hub to be screwed far in onto the sleeve or quite far out upon it without exposing the threads 130.

The inner end of the sleeve is shown in 95 Fig. 2 as threaded at 20 to receive the threaded end of a coupling nut 21 whose other end has an internal shoulder 22 swiveled behind a shoulder 23 at the outer end of the faucet 24. In Fig. 1 this arrangement is reversed so that the shoulder is on the sleeve and the thread is on the faucet. Either construction may be employed, or in fact other forms of coupling between the sleeve and the faucet may be 100 adopted without departing from the spirit of the invention. The construction shown in Fig. 3 is similar, except that the sleeve 13 is continued through the lavatory member and threaded internally at its outer end as 110

at 90° so as to form in effect a tail piece. Here again the supply pipe 1 is continuous from its juncture with the service pipe to the tail piece, into which threads 9 are 5 screwed so as to form a tight joint outside the wall or beneath the slab, without the use of the flanges and couplings usually employed at those points. The outer nut 10 is shown as screwed upon the exterior 10 threads 130 of the tail piece, instead of upon the threads of the supply pipe as in the other cases.

In applying these forms of fitting the supply pipe is first put in place with its 15 threaded end through the aperture in the lavatory member, and then a juncture is made with the service pipe. The outer nut is next set up to approximately its proper 20 position, and then the sleeve is adjusted so that the faucet when applied shall stand about where desired. If a compound faucet is to be attached, care is taken that the sleeves are adjusted so as to be truly parallel 25 and to project within the tub for equal distance. Next the inner nut with its flange is set up against the inner face of the member, and then both nuts are tightened to hold the fitting firmly in place. The single or compound faucet is then brought into position, 30 and the stub ends of the faucets are coupled to the exposed ends of the sleeves.

In order to make a finished job the outer or threaded ends of the sleeves should be hidden by the inner ends of the inner nuts 35 as above explained. This it will be seen that this improved fitting does not require an accurate adjustment of the outer or lower nut in positions where it is difficult for the 40 plumber to work, as he can make his last adjustment in plain view inside the tub or above the slab, and of course he can readily couple the faucets in the same position.

With tubs having large rims or with basins having flanges or deep bowls it may 45 be desirable to use winged nuts on the outside or underside so that they can be set up by hand and the final adjustments be made with the inner nuts which are in plain view.

What is claimed as new is:

50 1. The combination with a lavatory member having an aperture in its wall, of a supply pipe, a sleeve threaded onto the exterior of the free end of said pipe, said pipe and sleeve each having a clamping member movable solely on itself, said members positioning the fitting relative to the lavatory member, and a faucet removably secured to said sleeve.

2. The combination with a lavatory member 55 having an aperture in its wall, of a supply pipe having a threaded end, a sleeve screwed thereon, a faucet, means for detachably connecting said sleeve and faucet, a nut screwed on the pipe outside said wall, and a flange screwed on the sleeve inside

said wall and whose hub has an annular extension on its inner face provided with a smooth bore adapted to surround said sleeve.

3. The combination with a bath tub having an aperture in its wall; of a supply pipe 70 having a threaded end, a sleeve screwed thereon and having part of its exterior smooth, a faucet, means for detachably connecting said sleeve and faucet, a nut screwed on the pipe outside said wall, and a flange 75 screwed on the sleeve inside said wall and whose hub has an annular extension on its inner face provided with a smooth bore adapted to project over the smooth portion of said sleeve.

4. The combination with a lavatory member having an aperture in its wall; of a supply pipe having a threaded end projecting therethrough, a sleeve screwed thereon, a faucet, means for detachably connecting said 80 sleeve and faucet, a nut screwed on the pipe outside said wall, and a flange inside said 85 wall carried solely by and adjusted with the sleeve and having a wrench hold on its inner face.

5. The combination with a lavatory member having an aperture in its wall; of a supply pipe having a threaded end projecting therethrough, a sleeve screwed thereon and exteriorly threaded at its outer end, a faucet, means for detachably connecting said 90 sleeve and faucet, a nut screwed on the pipe outside said wall, and a flange inside said 95 wall screwed on the exterior threads of said sleeve.

6. The combination with a bath tub having an aperture in its wall; of a supply pipe having a threaded end projecting therethrough, a sleeve screwed thereon and exteriorly threaded at its outer end, a faucet, 105 means for detachably connecting said sleeve and faucet, a nut screwed on the pipe outside said wall, and a flange having interior threads solely engaging the exterior threads 110 of the sleeve and a wrench hold on its inner face.

7. The combination with a bath tub having an aperture in its wall; of a supply pipe having a threaded end projecting therethrough, a sleeve screwed thereon and exteriorly threaded from its outer end for a portion of its length, a faucet, means for detachably connecting said sleeve and faucet, a nut screwed on the pipe outside said wall, and a flange inside said wall having a 115 threaded opening adapted to fit and screw on the exterior threads of said sleeve and a wrench hold on its inner face having a smooth opening adapted to pass over the unthreaded portion of said sleeve.

8. The combination with a lavatory member having an aperture in its wall; of a supply pipe having a threaded end projecting therethrough, a sleeve screwed thereon and having an exterior shoulder at its inner 120 125

end, a faucet having threads on its extremity, a coupling nut having a shoulder swiveled behind that on the sleeve and internal threads engaging those on the faucet, a nut 5 screwed on the pipe outside said wall, and a flange carried solely by the sleeve inside the wall and having a flange adapted to clamp against it.

9. The combination with a bath tub having an aperture in its wall; of a supply pipe 10 having a threaded end projecting therethrough, a sleeve screwed thereon and exteriorly threaded at its outer end, a shoulder on the sleeve at its inner end, a faucet having threads at its extremity, a coupling nut 15

having a shoulder swiveled behind that on the sleeve and threads detachably engaging those on the faucet, a nut screwed on the pipe outside said wall, and a flange inside said wall whose hub is internally threaded 20 and screwed onto the exterior threads of said sleeve.

In testimony whereof I have hereunto subscribed my signature this the 21st day of October, A. D. 1907.

PHILIP MUELLER.
